UNITED STATES PATENT OFFICE.

NILS DAVID LEVIN, OF COLUMBUS, OHIO, ASSIGNOR TO THE JEFFREY MANUFACTURING COMPANY, OF COLUMBUS, OHIO, A CORPORATION OF OHIO.

MINING-MACHINE.

1,290,595.

Specification of Letters Patent.

Patented Jan. 7, 1919.

Application filed October 22, 1912, Serial No. 727,230. Renewed March 26, 1917. Serial No. 157,586.

To all whom it may concern:

Be it known that I, NILS D. LEVIN, a citizen of the United States, residing at Columbus, in the county of Franklin and State of Ohio, have invented certain new and useful 5 Improvements in Mining-Machines, of which the following is a specification, reference being had therein to the accompanying drawings.

10 This invention relates especially to mining machines of the front thrust or breast type and in trucks for use in combination with such machines for transporting them.

15 The principal object of the invention is to provide an improved arrangement of gearing and power transmitting mechanism for driving cutters, for feeding the cutter frame forward and backward on the bed frame, and for driving the truck upon which the machine may be placed for transportation.

20 In the accompanying drawings I have shown one embodiment of my invention, but it will be understood that many modifications and changes may be made without departing from the spirit of my invention as 25 set forth in the claims which are hereto appended.

In the drawings,

30 Fig. 1 is a plan view of a mining machine embodying my invention.

Fig. 2 is a side elevation.

Fig. 3 is a longitudinal sectional view of a part of the machine taken along the line 3—3 of Fig. 1.

35 Fig. 4 is a fragmentary view partly in section and partly in elevation of the driving gearing.

Fig. 5 is a detail view taken looking upward at the clutch element at the lower end of the drive shaft.

40 Fig. 6 is a detail view taken looking upward at the drive sprocket for the cutter chain.

Fig. 7 is a side elevation showing the mining machine in place on the truck.

45 Fig. 8 is a fragmentary plan view showing an automatic reversing mechanism. In this view the starting box is omitted for the sake of clearness.

50 Fig. 9 is a side elevation of the mechanism shown in Fig. 8.

Fig. 10 is a fragmentary view in section on the broken line 10—10 of Fig. 11.

Fig. 11 is a vertical section on the broken line 11—11 of Fig. 10.

Referring to the drawings, 1 represents as 55 a whole the main bed frame of the machine which may be of any usual or preferred construction. For present purposes it will be sufficient to point out that it comprises floor engaging shoes 2, 2^a, and longitudinal guides 60 or rails 3, 3, supported on the shoes. These rails are connected at their ends by means of cross members 4 and 5.

6 is a carriage slidably mounted upon the rails 3, 3. This carriage 6 comprises the 65 frame of a motor 7 and a plate or casting 8 secured to the motor frame. Secured to or formed on the frame of the motor and the casting 8 are laterally projecting lugs 9, 9, which engage the rails 3, 3, and support the 70 carriage.

10 represents as a whole the cutter frame. This frame is triangular in outline and comprises the forward head 11 and the side rails 12, 12. There is also a central guide bar 75 12^a which is secured at its forward end to the central part of the head 11 and comprises channel bars 12^b, 12^b, placed face to face. The cutter frame is slidably supported at the forward end of the bed frame by means of 80 a suitable bearing formed in a standard 2^b which is secured to the cross bar 5 and carries at its lower end the shoe 2^a. At the rear end of the cutter frame the bar 12^a and the rails 12, 12, are secured to a block 13 which 85 is slotted to receive bolts 13^a, 13^a, extending through holes in the casting 8 (see Figs. 3, 10 and 11). By means of a screw 13^b threaded in the block 13 and engaging the casting 8, the cutter frame may be adjusted with respect to the carriage. After the adjustment the frame can be locked in adjusted position by means of the bolts 13^a, 13^a. The head 11 and the rails 12, 12, are provided with slots 90 or guides in which the cutter chain 14 can move. At the ends of the head 11 are sprocket wheels 15, 15, over which the cutter chain passes. At the rear the cutter chain passes over a sprocket wheel 16 mounted on the carriage in a manner to be described. 95 The connection between the cutter frame and the carriage being adjustable, as described, the parts can be moved to conform with the length of the cutter chain.

The motor 7 is preferably arranged with 105 its armature shaft in vertical position. A starting box 7^a is provided for controlling the motor. At the upper end of the armature shaft of the motor is a pinion 18 which

meshes with a large drive gear 19 which is keyed to a vertical drive shaft 20 in a manner to permit the shaft to move vertically. A casing 21 incloses the gears, this casing 5 being supported at its rear end on the motor frame and at its forward end on vertical pins or studs 21^a.

Downward movement of the shaft is permitted under the control of the nut 22 which 10 is threaded on the upper end of the shaft. The nut 22 is held in vertically fixed relationship to the gear wheel by means of the ring 23. The space beneath the ring 23 and surrounding the nut may be used as a reservoir 15 for oil for lubricating the shaft bearings.

24 is a drive element for the drums which will be described below. Preferably this drive element is a hollow shaft or rotatable 20 sleeve having a central aperture through which the shaft 20 extends. The hub 25 of the gear wheel 19 is journaled in the central aperture of the sleeve by means of the bearing bushing 26, and the lower parts of the 25 shaft are journaled in this aperture by means of the bearing bushings 27, 27. Formed on the sleeve 24 at the upper end thereof is a horizontal flange or disk 28. At the outer edge of this disk 28 there is provided 30 a spur gear 29 which is preferably formed as a separate ring secured to the disk.

Positioned below the disk 28 and secured to the frame of the motor 7 is a supporting 35 plate or bracket 30. This plate 30 is provided with a central aperture in which by means of a bearing bushing 31 there is journaled a hub 32 which is a part of the sleeve 24. By means of this bearing at 31 the upper 40 end of the shaft and the associated parts are supported.

Secured to the plate 30 and positioned directly beneath the gear ring 29 is a gear ring 32. The rings 29 and 32 are of the same size 45 but are provided with different numbers of teeth. For example, it may be considered that the ring 29 has ninety teeth and the ring 32 ninety-one teeth. 33 is a bearing pin secured at its upper end to the web of the gear 50 19 and supported at its lower end by means of a stirrup 34 also secured to the web of the gear. Rotatably mounted upon the pin 33 is a pinion 35 of sufficient width to engage the teeth on the ring 29 and also those 55 on the ring 32. It will be observed that on account of the difference in the numbers of teeth on the gears 29 and 32 the movable gear 29 will, for every revolution of the gear wheel 19, be moved with respect to the 60 fixed gear 32 through a distance equal to that represented by the extra teeth on the fixed gear. If the gears are provided with ninety and ninety-one teeth, respectively, the gear 29 will be moved through the distance represented by one tooth or one-nine-

tieth of a revolution for each complete revolution of the gear 19, and will be moved in the opposite direction.

The sleeve 24 has secured to it near its upper end a hub 36. Keyed to the sleeve 24 near its lower end is a hub 37. A collar 38 threaded on the sleeve engages the lower side of the hub 37 and the integral hub 32 engages the upper side of the hub 36. The two hubs are in this way held against being moved away from each other. The hub 37 is journaled in a bearing aperture of the plate 8 of the carriage by means of a sleeve 39. By means of this bearing at 39 the lower ends 75 of the sleeve 24 and of the shaft 20 are held 80 in position.

Formed integrally with the hub 36 is an outward projecting circular flange 40 which is provided at its outer edge with a downward projecting annular collar 41. Surrounding this collar 41 is a winding drum 42. Extending from the lower edge of the drum 42 is an inward projecting plate or web 43, the inner edge of which rests upon a ball bearing 44. This ball bearing is supported upon the hub 45 of a gear wheel 46. This hub 45 has threaded engagement with the sleeve 24. In the recess formed between the flange 40 and the web 43 are mounted the disks of a friction clutch 47. These 95 disks are connected alternately with the web 43 and the flange 41 in the manner which is well known. It will be clear that by means of the gear wheel 46 the hub 45 can be turned and raised or lowered because of its threaded engagement with the sleeve 24. As the hub 45 is raised the web 43 and the drum 42 are raised and the friction disks of the clutch 47 are forced into engagement with each other. When the hub 45 is lowered the pressure 100 between the disks of the clutch is relieved. In this way the drum 42 can be connected with or disconnected from the flange 40, the hub 36, and the sleeve 24.

48 is a second drum of considerably less 110 diameter than the drum 42. This drum 48 is journaled on the sleeve 24 at 49. The drum 48 is positioned directly beneath the hub 45 and a ball bearing 50 is interposed between the hub and the drum. Between 115 the flange 48^a on the drum 48 and a flange 51 on the hub 37 before referred to there are located the disks of a friction clutch 52. These disks are alternately connected with the flange of the drum and with the flange 120 of the hub in the well known manner. When the hub 45 is turned in one direction by means of the gear wheel 46, the disks of the clutch can be forced into engagement with each other, and when the gear wheel is 125 turned in the other direction, the pressure between the disks can be relieved. In this way the drum 48 can be connected to or disconnected from the hub 37 and the sleeve 24. It will be noted that the same gear 130

wheel 46 and the same central hub 45 controls the two clutches 47 and 52. When the gear wheel is turned in one direction the clutch 47 is engaged and the clutch 52 is released. When the gear wheel is turned in the other direction the clutch 52 is engaged and the clutch 47 is released. The two clutches cannot both be engaged at the same time.

10 Journaled on the shaft 20 at the lower end thereof is the sprocket wheel 16 before referred to, over which the cutter chain 14 passes. This sprocket wheel 16 is provided at its lower edge with clutch teeth 53. The 15 lower end of the shaft 20 is provided with a clutch element 54 having radially extending teeth adapted to lie between and engage the teeth 53 when the shaft 20 is in its uppermost position. The teeth 54 can be disengaged from the teeth 53 by turning the nut 22 by means of a suitable wrench and thus lowering the shaft 20. By lowering the shaft further the clutch element 54 can, when the machine is on a suitable truck, be 20 brought into engagement with a clutch element on the truck. A projection 55 on the carriage supports the sprocket wheel 16 when the shaft is lowered.

25 56 is a feed rope connected to be wound upon the smaller drum 48. The feed rope extends forward and is connected with the forward end of the main frame. Preferably this connection with the main frame is by means of a rotatable sheave or pulley 57 30 secured to the cross-piece 5, but it will be understood that if desired the rope may be connected directly with the cross-piece. When a pulley is used, the end of the rope is carried around the pulley and backward 35 to a point of attachment at 58 on the carriage.

Connected to the other drum 42 to be wound thereon is a retracting rope 59. This rope is carried from the drum backward to 40 a point of attachment at the rear end of the bed frame. Preferably the rope engages an idler sheave 60 on the carriage and the idler 61 on the bed frame. From the sheave 61 the rope passes to a hook 62 which is 45 pivoted at 63 to the cross-piece 4 of the bed frame. A lug or pin 64 supports the hook 62 against movement in one direction and the parts are so arranged that the line of tension from the rope is such as to force the 50 hook against the pin. It will be clear, however, that if the hook is moved to bring the line of tension at the other side of the pivot 63 the tension will swing the hook into such a position that the rope will be disengaged.

55 60 The reason for this construction will be referred to later.

For rotating the gear 46 and the hub 45 I provide a pinion 65 which meshes with the gear. This pinion is secured to a shaft 66 65 rotatably mounted in suitable bearings on

the casing 8. At the other end of the shaft 66 is a combined hand and gear wheel 67. It will be clear that by turning this wheel 67, the gear wheel 46 and the hub 45 may be rotated and one or the other of the clutches 70 47 and 52 engaged, the other one being simultaneously disengaged. When it is desired to cut a kerf in a coal face, the machine is moved into proper position and secured in place by means of jacks such as those indicated at 68 and 69. By means of the starting box 7a the motor is set in operation and power is transmitted from the motor through the gearing and the shaft 20 to the sprocket wheel 16 and the cutter chain 14. 80 The operator by turning the wheel 67 in the proper direction can engage the clutch 52 and connect the drum 48 with the drive sleeve 24. The feed rope 56 will then be slowly wound upon the drum and the carriage and cutter frame will be moved forward, the cutters cutting their way into the coal. During the forward movement of the carriage and cutter frame, the rope 59 will be unwound from the drum 42.

90 When the operator desires to stop the advance of the carriage on the bed he turns the wheel 67 in a counter-clockwise direction and correspondingly rotates the wheel 46, and the latter is, by the threads on the hollow shaft or sleeve, caused to move away from the feed drum, and this releases the clutch at 52, thus stopping the forward feed of the carriage and of the cutter frame. In order to cause the carriage receding devices 100 to operate he continues the movement, bodily, of the wheel 46, and its hub 45, until the thread causes the parts of the clutch at 47 to close, whereupon the rope 59 is tensioned, and the carriage and cutter frame are 105 drawn backward, the movement being subject to control by the clutch operating devices 67 and 65. This backward movement at once releases the wheel 67 from the rack 70 and rotation of the wheel is again possible. It will be noted that the two drums 48 and 42 are driven at the same speeds and it will also be noted that on account of the larger diameter of the drum 42 the backward movement will be much faster than the forward movement.

110 The backward movement of the carriage and cutter frame may be stopped manually by the operator or by automatic means such as will be described. In order to prevent injury to the machine in case the backward movement is not stopped in the normal manner, I provide the hook 62 which has been described for the attachment of the end of the rope 59. From an examination of Fig. 125 1, it will be clear that the continued rearward movement of the carriage will bring the frame of the motor 7 into engagement with the hook 62 and force it backward to a position such that the rope 59 will be re-

leased, thus stopping the backward movement.

As stated, the backward movement of the carriage and cutter frame can be stopped by 5 manually turning the handwheel 67. This movement must be in the counterclockwise direction and at a speed in excess of the normal rotation of the wheel. In order that this movement may be effected automatically, I 10 prefer to provide as shown in Figs. 8 and 9 a rack bar 71 which is slideable longitudinally in bearings 71^a, 71^a, on the main frame. At the forward end of the rack bar 71 there is pivotally connected a rack 71^b. This rack bar 15 71 is connected with a lever 72 which is pivoted at 73 to the cross piece 4 of the main frame. The lever 72 has a forward extending end 74 adapted to be engaged by the frame of the motor 7 when the carriage approaches its rearmost position. As the pivot 20 73 is near the end 74 of the lever, the engagement of the motor frame with this end 74 causes the other end to be moved forward at a relatively high speed, carrying with it the 25 rack 71^b. As the rack moves forward it engages the wheel 67 and rotates it in the counterclockwise direction at a speed greater than normal, thus causing a corresponding movement of the gear wheel 46 and the hub 30 45 ahead of the sleeve 24. This movement of the hub 45 ahead of the sleeve 24 causes it to be lowered, the clutch 47 being thus released.

The rack 71^b is adjustably supported preferably by means of an eccentric 71^c. By turning this eccentric the operator can release the rack and permit it to be lowered out of engagement with the wheel 67. The wheel 67 is thus freed and can be turned by 40 the operator to again connect the lower clutch 52 for feeding the carriage and cutter frame forward. It will be understood, of course, that before the carriage is again fed forward, the machine will have been moved 45 and secured in a new position.

In addition to the sheave 61 there is provided on the main frame a sheave 75 over which the rope 59 can be guided when detached from the hook 62. The end of the 50 rope can be attached at a fixed point and by winding the rope on the drum the machine can be moved about the mine room or onto a truck.

As is well understood, the sprocket wheel 55 which drives the cutter chain, in machines of the sort to which my invention relates, necessarily is mounted to rotate on an upright axis. In my improved machine the armature shaft of the motor, the rotary devices by 60 which the carriage is fed forward and retracted, and the various transmission gears between the motor shaft and the sprocket wheel and the said rotary devices, respectively, are all mounted to rotate about upright axes so that I am able to employ spur

gears only and to secure an exceedingly compact arrangement of the parts. Furthermore, by arranging the motor low down between the side rails of the bed frame and grouping the operating parts in front of the 70 motor, the over-all height of the machine is kept relatively small. It is to be noted also that the attainment both of general compactness and of a small over-all height is facilitated by the arrangement of the driving pinion at the upper end of the motor shaft. 75

In order that my improved machine may be readily transported from place to place about a mine, I preferably provide in combination with it a truck such as is shown in 80 Fig. 8. As to the details of this truck there may be variations but the construction which I deem most advantageous is shown in the drawings.

The frame of the truck comprises side 85 rails 78 which are connected by a number of cross bars. The truck frame carries front and rear axles 83, 84 to which are connected pairs of track wheels 85 and 86, respectively. The front wheels 85 are connected, as by 90 chain 86^a, to the rear axle 84. The wheels 85 are not connected directly to the axle 83 but are mounted on the outer end of crank arms 88. These arms are keyed to the ends of the axle 83. This construction 95 provides in effect an axle bent at its two ends, and the wheels 85 are thus mounted eccentrically with respect to the central part of the axle.

It will be observed that this cranked axle 100 construction makes it possible for the forward end of the truck to be raised and lowered by rotating the axle. When the forward end of the truck is in its lower position the mining machine can be readily 105 moved onto or off from it, and when the forward end of the truck is in its upper position the truck is adapted to be moved along the track. In moving the machine onto the truck the rope 59 is passed to the 110 rear between the sheaves 61 and 75, and is secured at a suitable point to the rear end of the truck. The operator by engaging the clutch 47 can cause the cable to be wound and the machine to be moved bodily along 115 the truck. To each of the crank arms 88 is secured an upstanding horn 89 in position to be engaged by a pin or roller 90 on the frame of the mining machine. When the pins 90 are forced into engagement with the 120 horns 89 by the continued movement of the mining machine, the axle 83 is rotated and the truck is raised to horizontal position.

When the mining machine is in proper position upon the truck the clutch element 54 125 at the lower end of the main power shaft 20 is in mating position over a clutch element 91 which is mounted on the truck frame for rotation about a vertical axis. This clutch element 91 is connected with a drive sprocket 130

wheel 92, there being preferably interposed between the clutch element and the sprocket wheel an intermediate drive plate 93 having right angled tongue and groove connections 5 respectively with the clutch element and the sprocket wheel. (See Figs. 4, 5 and 6). This construction permits the clutch element and the sprocket wheel to rotate about axes which are somewhat out of alinement. By 10 lowering the shaft 20 sufficiently by means of the nut 22 the clutch element 54 can be brought into the engagement with the clutch element 91 and power thus be transmitted from the mining machine motor to the truck. 15 At the rear end of the truck a vertical shaft 94 is provided. This shaft carries a sprocket wheel in horizontal alinement with the sprocket wheel 92 and over these two sprocket wheels there passes a drive chain 20 95. The vertical shaft 94 is connected by suitable gearing (not shown) with a transverse shaft 99. At one end of the shaft 99 is a sprocket wheel 101 which is in longitudinal alinement with a similar sprocket 25 wheel 102 on the axle 84. A chain 103 passes over these two sprocket wheels and serves to transmit power from the shaft 99 to the axles. It will be clear that by means of the devices which have been described, 30 power can be transmitted from the mining machine motor to the truck wheels.

On the rear end of the truck is mounted an electric cable reel 104 but said reel and the mechanism for driving and controlling 35 it need not be described herein.

In the present application I make no claim to the construction of the truck *per se* or to the combination of the electric cable reel mechanism with the truck, or to the 40 cable reel mechanism *per se*, as these subjects-matter are claimed, respectively, in my co-pending applications for mining machines and trucks, Serial No. 557,432, filed April 25, 1910, for mining machines and 45 trucks, Serial No. 579,798, filed August 31, 1910, and for cable winding mechanisms, Serial No. 664,037, filed December 5, 1911.

I heretofore referred to the present machine as being one of the "front thrust" or 50 "breast" class; that is to say, a machine having an elongated bed adapted to be made temporarily stationary, and also having a longitudinally reciprocating carriage below the top of the bed together with a cutting 55 apparatus, which is thrust into and drawn directly backward from the kerf under the coal by longitudinal movements of the carriage between the side bars of the bed. Machines of this class should be as narrow as 60 possible under all circumstances. Consequently, the cubic space required by a large motor has necessitated the extending of the motor upward or forward on longitudinal lines, both of which are objectionable.

65 I introduce a large and powerful motor,

utilizing the space at the rear of the other parts and disposing it so that its lower end is in a plane just above the floor from which it extends upward between the side rails of the bed. It is secured to the extreme rear 70 end of the carriage and has its upper end brought to a low plane, permitting the height of the machine to be reduced. I shorten the reciprocating structure by placing all of the rotating driving and transmitting parts on a single axis, placing the shaft 75 which supports and carries them directly in front of the motor.

What I claim is:—

1. In a breast mining machine of the 80 class described, the combination with the bed, the longitudinally reciprocable carriage on the bed, and the horizontally arranged chain cutter on the carriage, of the electric motor movable with the carriage and secured 85 thereto at its extreme rear end, and positioned to extend from a horizontal plane near the floor upward on lines between the side rails of the bed, and having a vertical armature shaft, the vertical power transmitting shaft geared directly to the armature shaft and connected directly to the cutter chain, the carriage moving mechanism and the rotary transmitting devices on said shaft for actuating the carriage moving mechanism. 90

2. In a breast mining machine of the class described, the combination with the bed, the longitudinally reciprocable carriage on the bed, and the horizontally arranged chain 100 cutter on the carriage, of the electric motor movable with and secured to the carriage at the extreme rear end, and positioned to extend from a horizontal plane near the floor upward on lines between the side rails 105 of the bed, and having a vertical armature shaft, carriage advancing means, means for receding the carriage, and a single power transmitting shaft arranged vertically, and geared directly to the armature shaft at its upper end, and connected at its lower end directly to the chain cutter, and two rotating elements both on the axis of said shaft, one connected to and actuating the carriage advancing mechanism, and the other connected 110 to and actuating the carriage receding mechanism, and both adapted to be separably connected to said shaft. 115

3. In a mining machine, the combination of a bed frame, a carriage and horizontally 120 arranged cutter frame longitudinally movable on the bed frame, a cutter chain supported on and guided by the cutter frame, a sprocket wheel rotating about a vertical axis and engaging the cutter chain to drive 125 it, a motor on the carriage with its drive shaft arranged vertically and connected with the sprocket wheel, two rotatable drums mounted on the carriage for rotation about the same vertical axis, power connections be- 130

tween the motor and the respective drums whereby one or the other can be rotated, a feed rope engaging one drum and connected with the forward end of the bed frame to 5 move the carriage and cutter frame forward as the said drum is rotated, and a retracting rope engaging the other drum and connected with the rear end of the bed frame to move the carriage and cutter frame back- 10 ward as the said drum is rotated.

4. In a mining machine, the combination of a relatively stationary bed frame, a carriage movable longitudinally of the bed frame, cutting mechanism comprising a cutter chain carried by the carriage and adapted to form a horizontal kerf in the base of the coal vein, a vertically disposed driving element mounted upon the carriage, means to rotate said driving element, a sprocket 15 wheel mounted upon said driving element and engaging the cutter chain to drive it, two winding drums rotatably mounted upon the driving element, clutches arranged to connect the winding drums with the driving element, controlling devices arranged to cause the engagement of either one of said clutches to drive its respective winding 20 drum and to prevent simultaneous engagement of the other clutch, a flexible draft member windable upon one of said drums and arranged to advance the carriage and cutting mechanism relative to the bed frame 25 when said drum is rotated, and a second flexible draft member connected to the other drum and arranged to retract said carriage and cutting mechanism when said second drum is rotated.

5. In a mining machine, the combination of a relatively stationary bed frame, a carriage movable longitudinally of the bed frame, cutting mechanism comprising a cutter chain carried by the carriage and adapted to form a horizontal kerf in the base of the coal vein, a vertically disposed driving element mounted upon the carriage, means to rotate said driving element, a sprocket 30 wheel mounted upon said driving element and engaging the cutter chain to drive it, two winding drums rotatably mounted upon the driving element, clutches arranged to connect the winding drums with the driving element, controlling devices arranged to cause the engagement of either one of said 35 clutches to drive its respective winding drum and to prevent simultaneous engagement of the other clutch, a flexible draft member windable upon one of said drums and arranged to advance the carriage and cutting mechanism relative to the bed frame 40 when said drum is rotated, and a second flexible draft member connected to the other drum and arranged to retract said carriage and cutting mechanism when said second drum is rotated.

6. In a mining machine, the combination of a relatively stationary bed frame, a carriage movable longitudinally of the bed frame, cutting mechanism comprising a cutter chain carried by the carriage and adapted to form a horizontal kerf in the base of the coal vein, a vertically disposed driving element mounted upon the carriage, means to rotate said driving element, a sprocket 45 wheel mounted upon said driving element and engaging the cutter chain to drive it, two winding drums rotatably mounted upon the driving element, clutches arranged to connect the winding drums with the driving element, controlling devices arranged to cause the engagement of either one of said 50 clutches to drive its respective winding drum and to prevent simultaneous engagement of the other clutch, a flexible draft member windable upon one of said drums and arranged to advance the carriage and cutting mechanism relative to the bed frame 55 when said drum is rotated, and a second flexible draft member connected to the other drum and arranged to retract said carriage and cutting mechanism when said second drum is rotated.

6. In a mining machine, the combination of a relatively stationary bed frame, carriage movable longitudinally of the bed frame, a cutting mechanism comprising a cutter chain carried by the carriage and adapted to form a horizontal kerf in the base 60 of a coal vein, a vertically disposed driving

element mounted upon the carriage, means to rotate said driving element, a sprocket wheel mounted upon said driving element and engaging the cutter chain to drive it, two winding drums rotatably mounted upon the driving element, clutches arranged to connect the winding drums with the driving element, controlling devices arranged to cause the engagement of either one of said clutches to drive its respective winding 70 drum and to prevent simultaneous engagement of the other clutch, a flexible draft member windable upon one of said drums and arranged to advance the carriage and cutting mechanism relative to the bed frame 75 when said drum is rotated, and a second flexible draft member connected to the other drum and arranged to retract said carriage and cutting mechanism when said second drum is rotated.

7. In a mining machine, the combination of a relatively stationary bed frame, a carriage movable longitudinally of said bed frame, cutting mechanism comprising a cutter chain carried by the carriage and adapted to form a horizontal kerf in the base of the coal vein, a vertically disposed driving element mounted upon the carriage, means to rotate said driving element, a sprocket wheel mounted upon said driving element and engaging the cutter chain to drive it, two winding drums rotatably mounted upon the driving element, clutches arranged to connect the winding drums with the driving element, a controlling wheel screw threaded to 100 the driving element and arranged to cause the engagement of one of said clutches to rotate one of said drums when said controller wheel is rotated in one direction relative to the driving element and to cause the engagement of the other clutch to rotate the other drum when said controller wheel is rotated in the other direction relative to the driving element, a flexible draft member windable upon one of said drums and arranged to advance the carriage and cutting mechanism relative to the bed frame when said drum is rotated, and a second flexible draft member connected to the other drum and arranged to retract said carriage and cutting mechanism when said second drum is rotated.

8. In a mining machine, the combination of a relatively stationary bed frame, a carriage movable longitudinally of said bed frame, a cutting mechanism comprising a cutter chain carried by the carriage and adapted to form a horizontal kerf in the base of the coal vein, a vertically disposed driving element mounted upon the carriage, means to rotate said driving element, a sprocket wheel mounted upon said driving element and engaging the cutter chain to drive it, two winding drums rotatably mounted upon the driving element, clutches arranged to connect the winding drums with the driving element, a controlling wheel screw threaded to 120 the driving element and arranged to cause the engagement of one of said clutches to rotate one of said drums when said controller wheel is rotated in one direction relative to the driving element, a flexible draft member windable upon one of said drums and arranged to advance the carriage and cutting mechanism relative to the bed frame when said drum is rotated, and a second flexible draft member connected to the other drum and arranged to retract said carriage and cutting mechanism when said second drum is rotated.

positioned between the winding drums and arranged to connect said drums with the driving element, a controlling wheel screw threaded to the driving element and arranged to cause the engagement of one of said clutches to rotate one of said drums when said controller wheel is rotated in one direction relative to the driving element and to cause the engagement of the other clutch 5 to rotate the other drum when said controller wheel is rotated in the other direction relative to the driving element, a flexible draft member windable upon one of said drums and arranged to advance the carriage 10 and cutting mechanism relative to the bed frame when said drum is rotated, and a second flexible draft member connected to the other drum and arranged to retract the carriage and cutting mechanism when said 15 second drum is rotated.

9. In a mining machine, the combination of a bed frame, a carriage and cutter frame longitudinally movable on the bed frame, a cutter chain supported on and guided by 20 the cutter frame, a sprocket wheel engaging the cutter chain to drive it, a clutch element on the sprocket wheel, a motor, a vertical drive shaft connected with the motor and mounted in axial alinement with the sprocket 25 wheel, a clutch element at the lower end of the shaft, a manually operable device for moving the clutch element vertically to bring it into or out of engagement with the clutch element on the sprocket wheel, two rotatable 30 drums mounted concentrically with the drive shaft, power connections between the motor and the respective drums comprising in each case a clutch adapted to be thrown into or out of operation, a feed rope engaging one 35 drum and connected with the forward end of the bed frame to move the carriage and cutter frame forward as the said drum is rotated, a retracting rope engaging the other drum and connected with the rear end of 40 the bed frame to move the carriage and cutter frame backward as the said drum is rotated, a wheeled truck upon which the mining machine can be supported, and a clutch element on the truck connected with 45 the wheels thereof, the said clutch element 50

being in position to be engaged by the clutch element at the lower end of the drive shaft when the mining machine is in place on the truck.

10. In a mining machine, the combination 55 of a bed frame, a carriage and cutter frame longitudinally movable on the bed frame, a cutter chain supported on and guided by the cutter frame, a sprocket wheel engaging the cutter chain to drive it, a motor on the carriage connected with the sprocket wheel, two rotatable drums mounted on the carriage, power connections between the motor and the respective drums comprising in each case a friction clutch adapted to be thrown 60 in or out of operation, a feed rope engaging one drum and connected with the forward end of the bed frame to move the carriage and cutter frame forward as the said drum is rotated, a retracting rope engaging the 65 other drum, means for detachably connecting the retracting rope with the rear end of the bed frame to move the carriage and cutter frame backward as the drum is rotated, and automatically acting means for detaching 70 the retracting rope from the bed frame when the carriage and cutter frame moves backward beyond a certain point.

11. In a mining machine, the combination 75 of a bed frame, a carriage and cutting apparatus longitudinally movable on the bed frame, means for effecting the longitudinal movement of the carriage and cutting apparatus on the bed frame comprising a power driven rotary drum, mounted on the carriage, a rope engaging the said drum, means for detachably connecting the rope to one end of the bed frame, and automatically acting means for detaching the rope from the bed frame when the carriage and cutting 80 apparatus pass beyond a certain point in their longitudinal movement on the bed frame.

In testimony whereof I affix my signature in presence of two witnesses.

NILS DAVID LEVIN.
